US00D861018S

(12) **United States Design Patent**
Anzures et al.

(10) Patent No.: **US D861,018 S**
(45) Date of Patent: **** Sep. 24, 2019**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Freddy Anzures**, San Francisco, CA (US); **Greg Apodaca**, Mountain View, CA (US); **Ismael Basso**, San Francisco, CA (US); **Imran Chaudhri**, San Francisco, CA (US); **Christopher Foss**, San Francisco, CA (US); **Jonathan P. Ive**, San Francisco, CA (US); **Matthew Dean Rohrbach**, San Francisco, CA (US); **Brian Andrew Schmitt**, San Francisco, CA (US); **Christopher Daryl Soli**, Mountain View, CA (US); **Wan Si Wan**, Sunnyvale, CA (US); **Christopher Wilson**, San Francisco, CA (US)

(73) Assignee: **Apple Inc.**, Cupertino, CA (US)

(**) Term: **15 Years**

(21) Appl. No.: **29/608,796**

(22) Filed: **Jun. 26, 2017**

Related U.S. Application Data

(63) Continuation of application No. 29/563,713, filed on May 6, 2016, now Pat. No. Des. 790,574, which is a continuation of application No. 29/540,698, filed on Sep. 26, 2015, now Pat. No. Des. 755,827, which is a continuation of application No. 29/537,751, filed on Aug. 28, 2015, now Pat. No. Des. 759,085, which is a continuation of application No. 29/457,338, filed on Jun. 9, 2013, now Pat. No. Des. 737,833.

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
